Atty.

UNITED STATES PATENT OFFICE.

EDWIN N. TAYLOR, OF CEDAR RAPIDS, IOWA.

VEHICLE SIGNALING DEVICE.

1,316,121.

Specification of Letters Patent. Patented Sept. 16, 1919.

Application filed August 17, 1918. Serial No. 250,343.

To all whom it may concern:

Be it known that I, EDWIN N. TAYLOR, a citizen of the United States, residing at Cedar Rapids, in the county of Linn and 5 State of Iowa, have invented certain new and useful Improvements in Vehicle Signaling Devices; and I do hereby declare the following to be a full, clear, and exact description of the invention, such as will 10 enable others skilled in the art to which it appertains to make and use the same.

This invention relates to automobiles and other conveyances, and has for its object to provide convenient means to indicate directions about to be taken by such conveyances.

As is well known, the usual manner of denoting the course to be taken by an automobile, when deviating from its direct course, is the throwing out of a hand on one side or 20 the other. This is at times inconvenient, as when a "left-hand" driver wishes to turn to the right, and must move from his sitting position in order to make his right hand visible at the right of the machine, or vice 25 versa, and is always inadequate at night. This invention provides a simple signaling device, operable by a touch, and giving a clear indication to those before or behind.

In the accompanying drawing, forming a 30 part of this specification, Figure 1 is an elevation of a device embodying my invention, as seen from the driver's seat in a left-hand driven car. Fig. 2 is a central, vertical section of the same. Fig. 3 is a central, horizontal section of a modified type of the same, adapted to be operated electrically. Fig. 4 is a central, vertical section of the device shown in Fig. 3. Fig. 5 shows a magnet and connections adapted to operate the device 40 shown in Figs. 1 and 2.

In the drawing, the numeral 1 denotes the cowl; 2 the steering-post; 3 the steering-wheel; 4 the wind-shield, and 5 the wind-shield support of an automobile. These are 45 of a familiar type, and need no description. My improved signaling device is herein shown attached to the wind-shield support, and at the left side of the car. It is to be understood, however, that it may be attached 50 at any other desired point on the car, and is supposed to be provided at both sides, though here shown only at one.

Referring more particularly to Figs. 1 and 2, the numeral 6 denotes a drum or casing 55 provided with a base 7, whose lugs 8 may be attached to the wind-shield support by clips

9. The lugs are also pierced at 10, so as to be bolted or screwed to a flat surface, if desired. In practice the casing is best formed of two sections, one having the base, and an 60 outer section 11 carrying the signal apparatus to be described presently. These parts are hinged at 12, so as to swing vertically, and a suitable catch at 13 latches them together. This is for convenience in attaching 65 and detaching the lamp 14 set in its socket 15, and preferably provided with a reflector 16 to throw its rays outwardly. The casing is designed to form a practically dust and 70 weather proof inclosure for an electric lamp, its switch, and electromagnets for operating the semaphore, when such electro-magnets are used for the purpose.

The outer portion of the casing is nearly cylindrical, closed at the upper half, and 75 open below, so as to allow for the swing of a semaphore 17 pivoted at its center. The outer portion of the semaphore is preferably formed to resemble an arrow, as seen from the front or back. Its inner portion 80 conforms to the shape of the casing, especially the upper part thereof, being an arc of a circle concentric to the pivot, and lying close to the curved part of the casing above it. This serves as a closure for the semaphore, 85 as well as the opening at the side of the casing from which the semaphore projects. It is of course important that rain, snow, or dust be excluded from the interior of the semaphore, especially when electrically operated. To be so operated practically the poise of the semaphore must be delicate, with but little preponderating weight at the outer end, and if while hanging down the semaphore partially fills with heavy matter of 90 any kind, the actuation of the semaphore is likely to be impaired. In practice it is made mainly of sheet metal, and painted a distinctive signal color, red or green. The inner, 95 forked ends may straddle the lamp, and to them are attached heavy plates 18 to nearly counterpoise the arrows, so that a very light pull will lift the arrow from its normal, depending position, indicated by the dotted lines, to a horizontal position, as shown. 100 The middle portions of the arrow are slotted, front and back, to form much more slender arrows 19. These are extended back to within the casing so as to form the feathers of the arrow, and corresponding holes 20 110 are formed in the casing, so that when in horizontal position a full, clear arrow of

light will be exhibited at night. These openings are closed on the inside of the main arrow by strips of colored glass, or the like transparency, red or green, as desired. The 5 construction of the semaphore is such that the glass need not be cut arrow-shaped, but may be simple rectangular strips, as indicated in Fig. 2.

To elevate the semaphore to signaling position a number of devices are herein shown. 10 In Figs. 1 and 2 a manually operating device is illustrated. Near the pivot of the semaphore is attached a pull-cord 21, passing through a hole 22 in the casing base, and 15 thence about sheaves 23 and 24, and up the steering-post to a connection with a small lever 25 clipped to the post. When thrown to the position shown in Fig. 1 the lever comes to a stop 26, and thus locks the semaphore in signaling position, since the pull of the cord is across the pivot of the lever. A touch releases the lever, when the semaphore drops to normal position, by reason 20 of a slight preponderance of weight in the outwardly extended part of it.

In Fig. 5 is shown the connection of a magnet with the pull-cord, so that the operator need not reach to the steering-post, but may manipulate an electric switch 27 attached to 30 the steering-wheel. A magnet 28 is closed into an electric circuit, as from a battery 29, by said switch, and actuates a bell-crank armature 30, to the long arm of which the pull-cord connects.

35 Provision is made for the lighting of an electric lamp to illuminate the semaphore, when it reaches signaling position. Referring to Fig. 2 a simple, spring-blade circuit-closer 31 is shown mounted near the base of the casing. This switch is in circuit with a source of electrical energy 32, through the conductors *a*, *b* and *c*. When the semaphore reaches the horizontal a shoulder 33 has engaged the upper blade of the 40 switch and closed the circuit. As soon as the semaphore is released the switch automatically opens.

The preferred device for raising the semaphore is a directly connected magnet 34, as 50 shown in Figs. 3 and 4. By reason of its longer stroke, this is almost necessarily of the solenoid type. To the core of the solenoid is attached a short rack 35 engaging a partial pinion 36. The solenoid is energized from 37 by conductors *d*, *e* and *f*, in 55 the same manner as the magnet above described. From this an auxiliary circuit *g*, *h* and *i* leads to the lamp, so that the operator controls the semaphore and its lighting 60 by the switch 27. The principal advantage of this construction over the other magnetic control is that the connections from the steering-post switch to the casing are simply

electric wires, and may be made inconspicuous, or entirely concealed, whereas it is necessary to attach the other magnet at some suitable pulling point, as to the cowl, and connect the semaphore thereto by a pull-cord, not easily concealed.

65 Referring to Figs. 1 and 3, it will be seen that the outer end of the semaphore is formed as a reflector 38, to throw laterally the rays from the lamp opposite. This may be used with or without the reflector 16, above referred to.

70 To disconnect the lamp from the electric circuit, in the absence of a separate switch, such as a button-socket, the bulb may be unscrewed slightly to break the connection. This is rendered easy and simple by reason 75 of the hinged casing, the whole outer part of the apparatus being tilted up bodily, and without disturbing any of the operative parts. The device is designed to be used 80 with or without a light, the latter being unnecessary in the case of vehicles which operate only by daylight, such as trucks and the like.

85 Having thus described my invention, I claim:

90 1. In a signaling device, a casing composed of two parts hinged together, means for securing the same to some part of an automobile, an electric lamp seated in the attached part, a hollow semaphore pivoted 95 in the other part of the casing, and receiving interiorly light from said lamp, and means for tilting the semaphore to signaling position and simultaneously lighting the lamp, the casing being swingable to give access to the lamp and its accessories without disturbing said tilting means.

100 2. In a signaling device, a casing having a side opening to allow for the up and down swing of a semaphore, a hollow semaphore 105 having a forked inner end entering the opening in the casing, and provided with heavy cheek-plates to counterpoise the arm of the semaphore, and with lateral pivots bearing 110 in opposite sides of the casing, and disposed practically central to the weight of the semaphore, an electric lamp set in the casing opposite said opening, a switch therefor closed by the semaphore when elevated, a magnet, in the light circuit, a switch therefor, and 115 a connection of the magnet armature with the semaphore whereby a partial rotation is given to the semaphore pivot by the movement of said armature.

120 In testimony whereof I affix my signature in presence of two witnesses.

EDWIN N. TAYLOR.
